UNITED STATES PATENT OFFICE

ERIK E. HANSON, OF SAN FRANCISCO, CALIFORNIA.

FOLDABLE UMBRELLA.

1,036,226.

Specification of Letters Patent. Patented Aug. 20, 1912.

Application filed April 17, 1912. Serial No. 691,291.

To all whom it may concern:

Be it known that I, ERIK E. HANSON, a citizen of the United States, residing at the city and in the county of San Francisco and State of California, have invented new and useful Improvements in Foldable Umbrellas, of which the following is a specification.

This invention relates to a foldable umbrella.

10 The object of this invention is to provide an umbrella which is so constructed that the spreading ribs and the umbrella rod may be folded so as to occupy small space so that it can be readily packed in suit-cases, valises or the like, or carried in the pocket.

15 A further object is to provide a foldable umbrella of the above character, which is simple in construction and which can be easily and quickly operated both in folding and unfolding.

Further objects will appear in the following specification.

The invention consists of the parts and the construction and combination of parts 25 as hereinafter more fully described and claimed, having reference to the accompanying drawings, in which—

Figure 1 is a view of the umbrella in vertical section showing it in its open position. 30 Fig. 2 is a similar view showing the umbrella in the closed position. Fig. 3 is a similar view showing the umbrella in its folded position. Fig. 4 is a detail of the folding lock joint of the umbrella ribs. Fig. 35 5 is a side view of same. Fig. 6 is an end view. Fig. 7 is a detail vertical section of the foldable umbrella rod in the open or extended position. Fig. 8 is a similar view showing the umbrella rod in its folded closed 40 position. Fig. 9 is a section on the line X—X of Fig. 7. Fig. 10 is a section on the line Y—Y of Fig. 8. Fig. 11 is a detail in elevation of the worm sleeve. Fig. 12 is a side view of same. Fig. 13 is a section on 45 the line Z—Z of Fig. 12. Fig. 14 is a detail in elevation showing the telescopic connection of the umbrella handle to the umbrella rod. Fig. 15 is a detail in elevation of the telescopic umbrella rod showing the device 50 for locking the telescopic members together.

In the drawings the spreading ribs of the umbrella are shown as constructed in two pieces, indicated at A and B, which are pivotally connected together at 2; the rib portion 55 B being pivotally connected at its inner

end, as at 3, to a disk 4 in the manner common in the ordinary umbrella construction.

The brace rod of the umbrella is indicated at 5 and is pivotally connected at 6 to the rib portions B and has its inner end pivotally connected at 7 to a swiveled yoke 8, mounted on a flange 9, carried by a worm sleeve 10.

The disk 4 is rigidly mounted on a tubular rod 11 which extends a short distance on one side of the disk 4 to form the umbrella tip and extends inwardly from the disk 4 a distance approximately one-third of the length of the ordinary umbrella rod. The rod 11 is formed with spiral ribs 12 which extend 70 from the underside of the disk 4 to a point approximately midway of the length of the rod 11, terminating at the lower end in a collar 13. The sleeve 10 is mounted on the rod 11 and is formed with internal spiral 75 grooves which engage the spiral ribs 12 and is slideable thereon in such a manner, that when the sleeve 10 is reciprocated on the rod 11 it will be caused to turn a short distance thereon. The purpose of the sleeve 10 is to 80 actuate the brace rods 5 so as to open and close the umbrella by the reciprocation of the sleeve; the turning motion of the sleeve transmitting a pulling or pushing movement to the brace rods 5 according to the up or 85 down movement of the sleeve.

Extending into the tubular rod 11 is a similar rod 14 which is formed with a longitudinally extending slot 15 into which a pin 16, mounted on the rod 11, extends, 90 which pin 16 serves to lock the rods 11 and 14 together, as will presently be described. The lower end of the rod 14 extends into a tube 17 on which the handle portion 18 of the umbrella is mounted; the handle portion 18 being here shown as consisting of a flat disk having an inwardly extending annular flange on its outer periphery. The rod 14 and the tube 17 are connected together by means of a pin 19 on the former 95 which extends through a longitudinally extending slot 20 formed in the latter, as shown in Figs. 7 and 14. Surrounding the rod 14 is a collar 21 which is spaced some distance from the worm sleeve 10 and is connected thereto by means of flexible rods 22; the sleeve forming a handhold, by means of which the worm sleeve 10 is reciprocated on the rod 11, as will presently be described. 100

When the umbrella is in the open extend- 110

ed position, as shown in Figs. 1 and 7, the rod 14 will be disposed in its lowermost position with relation to the rod 11, with the pin 16 extending into a bayonet slot 15' in such a manner that the rods 11 and 14 will be rigidly connected together at this point, and the tube 17 will be disposed in its outermost position on the rod 14 with the pin 19 disposed in a bayonet slot 20', as shown in Fig. 14, so as to securely lock the sleeve 17 and the rod 14 together at this point. The worm sleeve 10 will now be disposed at its lowermost position on the spiral ribs 12 adjacent to the collar 13.

When the worm sleeve 10 is in its lowermost position, the brace rods 5 and the rib portions A—B will be disposed in their extended positions; the rib portion A being locked to the portion B by means of a locking device carried by the rib portion B. This locking device is shown in detail in Figs. 4, 5 and 6 and consists of a ferrule 23 rigidly mounted on the rib portion B. This ferrule is formed with a longitudinally extending curved slot 24 on one side thereof into which the rib portion A extends, as shown in Fig. 4; the portions of the ferrule extending on each side of the rib portion A and projecting over the underside thereof acting to securely lock the rib portions A and B together.

In closing the umbrella, the worm sleeve 10 is moved upwardly on the spiral ribs 12 by means of the sleeve 21 and ribs 22; the worm sleeve 10 in traveling upward on the spiral ribs 12 turning approximately one-fourth of a revolution from the position shown in Fig. 9 to that illustrated in Fig. 10. The worm sleeve 10 in rotating carries the inner ends of the brace rods 5 therewith. When the worm sleeve 10 has reached its uppermost position adjacent to the disk 4, the inner ends of the brace rods 5 will have moved around the rod 11 nearly one-fourth the distance therearound. By reason of the outer ends of the brace rods 5 being connected to the ribs A—B, the movement of the brace rods 5 around the rod 11 will exert an inward pull upon the spreading ribs A—B, so as to cause the latter to fold against the brace rods 5, as shown in Fig. 2; the brace rods 5 then assuming an angular position in relation to the rod 11 and the ribs A—B. The swiveled connection of the brace rods 5 to the flange 9 admits of the sleeve 10 turning without twisting the brace rods. This action of the sleeve 10 or the brace rods 5 in moving up on the rod 11 serves to theoretically decrease the length of the latter and increases their lengths when the sleeve is moved down so as to spread the ribs A—B.

Means are provided for temporarily locking the worm sleeve 10 adjacent to the disk 4 so as to prevent the umbrella ribs A—B

from spreading when the umbrella is inverted. This means is here shown as consisting of a pawl 25 mounted on the worm sleeve 10, with its outer end extending through a slot in the worm sleeve 10 so as to engage a notch 26 formed in one of the ribs 12 when the worm sleeve 10 is in its uppermost position adjacent to the disk 4. A spring 27 bears against the inner end of the pawl 25 in such a manner as to normally retain the outer end in its innermost position. Mounted on the worm sleeve 10 is a loose collar 28 to which the rods 22 are connected; this collar 28 having a short reciprocal movement on the worm sleeve 10. Formed on the collar 28 is a beveled tongue 29 which extends over the inner end of the pawl 25, as shown in Figs. 11, 12 and 13.

When the sleeve 21 is pulled outwardly to open the umbrella from the position shown in Fig. 2 to the position shown in Fig. 1, the collar 28 moves a short distance on the sleeve 10 so as to cause the tongue 29 to bear down upon the inner end of the pawl 25 and thereby move the latter out of engagement with the notch 26 on the rib 12 and free the worm sleeve 10, so that a continued pull upon the sleeve 21 will move the worm sleeve 10 downwardly on the spiral ribs 12, thereby rotating the worm sleeve 10 and the flange 9 approximately one-fourth of a revolution from the position shown in Fig. 10 to that shown in Fig. 9 and spreading the umbrella ribs A—B into their open positions. This spreading of the umbrella ribs into the open position is occasioned by the rotary movement given the sleeve 10 as it moves downward on the spiral ribs 12; the combined downward and rotary movement of the sleeve 10 acting to move the brace rods 5 longitudinally against the spreading ribs B, with the result that the latter will be rocked outwardly on their pivots 3.

In opening the umbrella, the rib portions A are moved from the position shown in Fig. 3 to that shown in Fig. 2, by hand, the rib portions A, however, not extending into the slot 24 until the rib portions B are about to assume their spread positions. The rib portions B in moving outward carry the rib portions A therewith, and as they near their extended positions the latter enter the slots 24 by reason of the slots 24 being disposed below the rib portions A.

When it is desired to fold the umbrella, it is first closed into the position shown in Fig. 2, whereupon the rib portions A are disengaged from the ferrules 23 by giving them a slight twist so that they will pass through the curved slot 24 formed in the ferrules and thereby permit of the rib portions A being folded back over the rib portions B into the position shown in Fig. 3. The pin 19 on the rod 14 is then moved

from the bayonet slot 20' into the slot 20 so that the tube 17 may be telescoped with the rod 14, as shown in Fig. 8, and the rod 14 is turned so that the pin 16 on the tubular rod 11 will pass from the bayonet slot 15' into the slot 15 so that the rod 14 may be moved endwise into the tubular rod 11, as shown in Fig. 8. When this is done, the jointed ends of the spreading ribs A—B 16 will extend into the flange formed on the umbrella handle 18, as shown in Fig. 3, thereby locking the umbrella in its folded position. The umbrella ribs A—B are covered with a suitable fabric in the usual 15 manner.

Having thus described my invention, what I claim and desire to secure by Letters Patent is—

1. In a foldable umbrella, a telescopic, 20 tubular umbrella rod, spreading ribs pivotally connected to the umbrella rod, spiral ribs formed on the umbrella rod, a worm sleeve slidable on and engaged by said spiral ribs, and brace rods connecting the worm 25 sleeve to the spreading ribs.

2. In a foldable umbrella, a telescopic, tubular umbrella rod, spreading ribs pivotally connected to the umbrella rod, spiral 30 ribs formed on the umbrella rod, a worm sleeve slidable on and engaged by said spiral ribs, brace rods connecting the worm sleeve to the spreading ribs, and swiveled yokes carried by the worm sleeve to which the inner ends of the brace rods are attached.

3. In a foldable umbrella, a telescopic, tubular umbrella rod, spreading ribs pivotally connected to the umbrella rod, spiral 40 ribs formed on the umbrella rod, a worm sleeve slidable on and engaged by said spiral ribs, brace rods connecting the worm sleeve to the spreading ribs, swiveled yokes carried by the worm sleeve to which the inner ends of the brace rods are attached, and 45 means for locking the worm sleeve to the umbrella rod, consisting of a pawl mounted

on the worm sleeve, and a notch formed in the umbrella rod.

4. In a foldable umbrella, a telescopic, 50 tubular umbrella rod, spreading ribs pivotally connected to the umbrella rod, spiral ribs formed on the umbrella rod, a worm sleeve slidable on and engaged by said spiral ribs, brace rods connecting the worm sleeve to the spreading ribs, swiveled yokes carried by the worm sleeve to which the inner ends of the brace rods are attached, means 55 for locking the worm sleeve to the umbrella rod, consisting of a pawl mounted on the worm sleeve, and a notch formed in the umbrella rod, and means for disengaging the pawl from the notch, consisting of a collar slidable on the worm sleeve and means for reciprocating said collar.

5. In a foldable umbrella, a telescopic, 60 tubular umbrella rod, spreading ribs pivotally connected to the umbrella rod, said spreading ribs pivotally divided adjacent to their centers, means for locking the divided portions of the spreading ribs together in 65 their open position, spiral ribs formed on the umbrella rod, a worm sleeve slidable on and engaged by said spiral ribs, brace rods connecting the worm sleeve to the spreading ribs, swiveled yokes carried by the worm 70 sleeve to which the inner ends of the brace rods are attached, means for locking the worm sleeve to the umbrella rod, consisting of a pawl mounted on the worm sleeve, and a notch formed in the umbrella rod, and 75 means for disengaging the pawl from the notch, consisting of a collar slidable on the worm sleeve and means for reciprocating said collar.

In testimony whereof I have hereunto set 80 my hand in the presence of two subscribing witnesses.

ERIK E. HANSON.
